EX

OR D 3,894

United States Patent Office.

JOHN R. JERAULD AND HENRY L. HOLMES, OF PROVIDENCE, RHODE ISLAND.

Design No. 3,894, dated March 8, 1870.

DESIGN FOR A COLLAR-BOX.

The Schedule referred to in these Letters Patent and making part of the same.

To all whom it may concern:

Be it known that we, JOHN R. JERAULD and HENRY L. HOLMES, of the city of Providence, county of Providence, and State of Rhode Island, have originated and designed a new Pattern for Paper-Collar Boxes, of which the following is a full, clear, and exact description, reference being had to the accompanying drawings making part of this specification.

Figure 1 is a round-cornered telescopic box, the cover shutting to the bottom. In the center of the cover is the band *a*, fastened to the cover and running around it, and having two ornamental edges, *b*. The remainder of the band is covered with paper corresponding to that of the cover.

Figure 2 is square box. The tube *a* forming the

box, and having two covers, *b* and *b'*. One, *b'*, fastened to the tube, and forming the bottom, and also the band, as in fig. 1.

Claim.

What we claim as our invention, and desire to secure by Letters Patent, is—

The band, either as the bottom or center of box, as being ornamented, and also as a novelty in the manufacture of paper-collar boxes, herein set forth.

JOHN R. JERAULD.
HENRY L. HOLMES.
